UNITED STATES PATENT OFFICE.

RICHARD M. BROWNE, AND THOMAS D. SCOTT, OF NEW YORK, N. Y.

APPARATUS FOR RAISING SUNKEN VESSELS.

1,240,538.

Specification of Letters Patent. Patented Sept. 18, 1917.

Application filed March 26, 1917. Serial No. 157,353.

To all whom it may concern:

Be it known that we, RICHARD M. BROWNE and THOMAS D. SCOTT, both subjects of King George V, and resident of the borough of 5 Manhattan, in the city, county, and State of New York, have invented certain new and useful Improvements in Apparatus for Raising Sunken Vessels, of which the following is a specification.

10 This invention relates to means for raising sunken ships, and our improvements are directed particularly to a novel form of pontoon and means whereby a series of these pontoons may be more serviceably attached 15 directly to the hull of a vessel for the purpose of insuring the permanency of their connection while engaged in the operation of floating the vessel. The means for attaching pontoons to sunken vessels now in 20 vogue, which comprises the use of chains passing around the ship's bottom, having means of connection with pontoons at the opposite sides of the ship, possess an element of instability; and, in addition to the liability of breakage, are apt to become shifted 25 or displaced under the strains imposed by the dead weight to be raised; so that it frequently occurs that a ship raising undertaking, when progressing with apparent success, after the main work of placing the 30 pontoons and connecting them has all been accomplished, may prove entirely unavailing, involving a loss of time, effort and expense.

35 Therefore our invention consists in the provision of pontoons, which may be rectangular in cross-section, and having an extensive flat surface capable of lying snugly up against the side of the sunken vessel, each 40 pontoon having means, as a surrounding flange, whereby it may be bolted directly to the vessel. A row of these pontoons may be arranged and secured along each side of the vessel to afford equi-poised means of 45 buoyant lift.

For simplified convenience of employment, the pontoons may be floated to the scene of the wreck, and for this purpose they are constructed in the form of vessels with a 50 suitable flotation bottom, opposed to a flat deck portion, which latter is intended, under service conditions, to lie against the ship's side. Hence, when these pontoons are in the vicinity of the wreck, they are submerged 55 by the influx of water, through suitable

valved orifices, in such manner that in submerging they will incline toward a position where the flat deck portion assumes a vertical position, to be parallel or approximately parallel with the side of the vessel, 60 thereby enabling a more convenient manipulation of the pontoons in placing them in the desired operative positions relatively to the sunken ship.

Our invention further comprises means 65 whereby the pontoons, with the aid of ropes and pulleys, operated from a wrecking vessel above, may be drawn into the desired positions relatively to the ship's sides for attachment thereto, and still further our invention includes means for temporarily holding the pontoons in their arranged operative positions relatively to the ship while the process of securely bolting said pontoons to the ship's sides is being accomplished. 75

Other features and advantages of our said invention will hereinafter appear.

In the drawings:

Figure 1 is a plan view of one of our improved pontoons, partly in horizontal section. 80

Fig. 2 is a side sectional elevation thereof.

Fig. 3 is a partial, transverse section of a ship's hull, with a pontoon, partly in section, attached thereto. 85

Fig. 4 is an enlarged detail showing the bolted, flanged connection between pontoon and ship, and

Fig. 5 is a diagrammatic view showing a method of directing a submerging pontoon 90 into its operative position.

Primarily, the purpose of our invention is to so securely attach pontoons to a sunken vessel that they will not become dislodged under service strains. Therefore we provide a pontoon, as 1, which has a flat deck surface 2, with a flange 3 that may extend around said surface 2, and may be provided with bolt holes 4, the latter to receive bolts, as 5, which serve to bolt the pontoon to the 100 side of the sunken ship, as 6. Obviously, the bolted connection may be made so secure that the pontoon becomes an integral part of the ship's hull. While the particular conformation of the pontoon employed may be 105 varied, we have illustrated it herein as a rectangular oblong, having reinforce ribs, that form being convenient and lending itself to certain advantages of structural strength and rigidity. Lengthwise thereof the pon- 110

toon may be divided, as by the bulkheads 7, 8, forming compartments which lie in the same horizontal plane when the pontoon is floating as upon its bottom 9, but which are 5 in superposed relation when the pontoon is upended in its operative position (Fig. 3).

The purpose of these compartments is to enable the pontoon, while submerging, to change the angularity of its position. Thus, 10 assuming a pontoon to be floating, as in Fig. 5, and having arrived over the ship to be raised, then by opening an orifice 10 in the lower end portion of compartment 11, water will enter that compartment and by its 15 weight cause that portion of the pontoon to submerge in advance of the remainder of the pontoon, so that the pontoon will acquire the upended position shown in dotted lines in Fig. 5.

20 For further submergence the compartment 12 may then fill with water through a communicating orifice 13 in bulkhead 7, said orifice 13 being located near deck 2, to prevent passage therethrough until compartment 11 is filled. The head of air in the pontoon will thus become compressed in the upper portion or compartment 14 thereof, and by its location will assist in maintaining the desired upended position of the 25 pontoon.

Guide ropes, as 15, extending from the pontoon, and engaging with pulleys 16 which have been suitably secured to the sunken ship, may be controlled from the 30 wrecking vessel 17, to draw the pontoon into the desired position against the side of the ship's hull, to which it can be temporarily secured as by turnbuckle connection 18, thereby bringing and holding the flange 3 into the 35 desired close connection with the hull of the ship to enable the bolting operation to be performed.

40 Preferably the bolt holes in the flange can be so distanced apart that they occur in positions to coincide with the ribs in the ship's hull, in order that the bolting may be effected through said ribs, to enhance the strength of the union.

The air tubing 19, through which air is 45 forced, as from a pump on the wrecking vessel, to displace the water in the pontoons, when a series of the latter have been secured to the sunken ship, may be connected with the pontoons as at 20. This tubing may also 55 serve for regulating the air pressure in the pontoon while submerging.

Closure means of desired character may be provided for the orifice 10, but are not illustrated herein as forming no part of our 60 present invention.

Variations may be resorted to within the

spirit and scope of our said invention, and parts thereof used without others.

We claim:

1. A pontoon having a flat side arranged 65 to lie snugly against the side of a vessel, and having a co-extensive flange whereby said pontoon may be bolted to the vessel.

2. A salvage pontoon having a deck portion attachable to the side of a sunken ship, 70 and means whereby said pontoon submerges angularly, to dispose its deck portion vertically, for such attachment.

3. A salvage pontoon having a deck portion attachable to the side of a sunken ship, 75 vertical lengthwise compartments in said pontoon, and means for admitting water at a lower portion of one of said compartments to upend said pontoon and dispose its deck portion vertically, for such attachment.

4. The improvement in the art of ship construction wherein a sunken vessel is provided with a series of salvage pontoons, which are rigidly bolted to the sides of said vessel to thereby become an integral part of 80 its fabric.

5. As a new article of manufacture a salvage pontoon in the form of a submersible, flotation vessel having a flat deck portion, said deck portion having an extending 90 flange, whereby, when said pontoon is fitted with its deck portion lying against the side of a sunken ship, it may be bolted to the ship and thus become an integral part of the same.

95 6. A salvage pontoon having a flat side with an extending flange, said flat side and flange arranged to fit closely against the side of a sunken vessel, and said flange having a series of bolt holes, whereby under the provision of registering bolt holes formed in the vessel's side, connecting bolts may integrally unite said pontoon and vessel.

7. A salvage pontoon having a flat side with an extending flange, said flat side and 105 flange arranged to fit against the side of a sunken vessel, and said flange having a series of bolt holes, arbitrarily spaced horizontally, whereby, under the provision of registering bolt holes formed in the vessel's 110 side and piercing the ribs of the hull, connecting bolts may integrally unite said pontoon and vessel.

Signed at the borough of Manhattan in the city, county and State of New York this 115 23rd day of March A. D. 1917.

RICHARD M. BROWNE.
